CLAIM

The ornamental design for a pneumatic actuator for an electrical switch, as shown and described.

DESCRIPTION

FIG. 1 is a top plan view of a pneumatic actuator for an electrical switch showing our new design;

FIG. 2 is a front elevational view thereof, the rear elevational view being a mirror image;

FIG. 3 is a right side elevational view thereof, the left side elevational view thereof being a mirror image; and, FIG. 4 is a bottom plan view thereof.

FIG. 1

FIG. 2

FIG. 3

FIG. 4
